Alexander Tobias Inventor

By his Attorney

Frank Kent

UNITED STATES PATENT OFFICE.

ALEXANDER TOBIAS, OF BROOKLYN, NEW YORK.

COMB OR SIMILAR ARTICLE.

Application filed June 6, 1922. Serial No. 566,315.

To all whom it may concern:

Be it known that I, ALEXANDER TOBIAS, a citizen of the United States, residing at Brooklyn, in the county of Kings and State of New York, have invented certain new and useful Improvements in Combs or Similar Articles, of which the following is a specification.

This invention relates to articles, such as 10 combs, which are formed of a hard, brittle material, and therefore break easily in use. It is one object of this invention to provide such articles with a suitable reinforcement of a durable material, such as metal, which 15 will take up the strains to which the article is subjected.

It is a further object of this invention to provide a reinforcement of the kind described which may be utilized as a frame 20 upon which may be cast material such as vulcanite, bakelite or the like, preferably one which will take a surface polish, to form the article; and the frame is so formed that the cast material will be firmly held thereon.

25 Other objects and aims of the invention, more or less broad than those stated above, together with the advantages inherent, will be in part obvious and in part specifically referred to in the course of the following 30 description of the elements, combinations, arrangements of parts, and application of principles constituting the invention; and the scope of protection contemplated will appear from the claims.

35 In the accompanying drawings,

Fig. 1 is a vertical section illustrating my invention applied to a comb.

Fig. 2 is a vertical section taken on the line 2—2 of Fig. 1.

40 Fig. 3 is a perspective view of a portion of the reinforcing frame.

Fig. 4 is a view similar to Fig. 2 showing a modified form of frame.

Fig. 5 is a view similar to Fig. 2 showing 45 a second modification.

Fig. 6 is a view similar to Fig. 2 showing a third modification.

Referring to the drawings, I have illustrated my invention in connection with a 50 comb, but it will be understood that the invention may be applied to a wide range of similar articles. Essentially I provide a reinforcing frame 10 having the general configuration of the finished article, in this

case having back and teeth like the finished 55 comb, but on a smaller scale. The frame may be of a hard, durable material such as sheet iron, and the material 11 such as vulcanite or bakelite out of which the comb is to be formed is cast around said frame on 60 all sides thereof to completely enclose it.

In order to hold the cast material firmly 65 on the frame, the latter may be provided with openings 12 into which the cast material is run or pressed during casting to unite the material on both sides of the reinforcing frame. In addition to said openings other projecting members of the frame, in this case the teeth of the comb, may be 70 provided with corrugations or other surface irregularities to break the smooth surface and enable the cast material to grip the frame firmly. These irregularities may take the form of indentations 15 (as shown in Fig. 3), or of saw-teeth 16 (as shown in the modification of Fig. 4,) or of lateral 75 openings 17 extending through the teeth (as shown in the modification of Fig. 5). The smooth plane surface of the teeth may also be interrupted by forming the teeth of the frame as spirals 18, as shown in the modification of Fig. 6. It may be desirable to provide additional irregularities in the surface of the reinforcing frame in the form of shoulders 20 (see Figs. 4 and 5) extending outwardly from the front and rear surfaces, and serving to separate the material forming the back of the comb from the material forming the teeth.

80 In any of the above modifications the principle is the same, i. e., the provision of irregularities in the surface of the reinforcing frame to provide gripping members upon which the cast material may attach itself firmly to form a close union between 85 the frame and the outer material.

90 The above description represents an embodiment of the principles constituting this invention, and it will be apparent that various changes may be made within the 95 scope of the annexed claims.

Claims:

1. An article of the class described comprising a reinforcing frame having a back and teeth which conform to the finished article, long narrow openings and a shoulder in said back and a roughened portion on said teeth and material adapted to 105

be cast upon said frame to entirely cover the surface thereof.

2. An article of the class described comprising a reinforcing frame having a back and teeth which conform to the finished article, long narrow openings in said back and the teeth of said frame each having ir-

regularities in their surface and material adapted to be cast upon said frame to entirely cover the surface thereof.

In testimony whereof I affix my signature.

ALEXANDER TOBIAS
